UNITED STATES PATENT OFFICE

149,011

DESIGN FOR AN EGG BEATER OR THE LIKE

Wayne F. Owens, Sheridan, Wyo., assignor to Boeing Aircraft Company, Seattle, Wash., a corporation of Washington

Application March 23, 1946, Serial No. 127,882

Term of patent 14 years

(Cl. D44—29)

To all whom it may concern:

Be it known that I, Wayne F. Owens, a citizen of the United States, residing at Sheridan, in the county of Sheridan and State of Wyoming, have invented a new, original, and ornamental Design for an Egg Beater or the like, of which the following is a specification, reference being had to the accompanying drawing, forming part thereof.

I claim:

The ornamental design for an egg beater or the like, substantially as shown.

WAYNE F. OWENS.
